UNITED STATES PATENT OFFICE.

LOUIS C. LOEWENSTEIN, OF LYNN, MASSACHUSETTS, ASSIGNOR TO GENERAL ELECTRIC COMPANY, A CORPORATION OF NEW YORK.

CENTRIFUGAL COMPRESSOR.

1,287,367.

Specification of Letters Patent. Patented Dec. 10, 1918.

Application filed May 15, 1916. Serial No. 97,525.

To all whom it may concern:

Be it known that I, LOUIS C. LOEWENSTEIN, a citizen of the United States, residing at Lynn, in the county of Essex, State of Massachusetts, have invented certain new and useful Improvements in Centrifugal Compressors, of which the following is a specification.

The present invention relates to centrifugal compressors and has for its object to provide an improved structure for a compressor, particularly a multistage machine.

For a consideration of what I believe to be novel and my invention, attention is directed to the accompanying specification and the claims appended thereto.

In the accompanying drawings, Figure 1 is a longitudinal sectional view of a multi-stage compressor embodying my invention, the section being taken along the line 1—1, Fig. 2; Fig. 2 is a face view of the right-hand end section of Fig. 1; Fig. 3 is a section taken on line 3—3, Fig. 1; Fig. 4 is a section taken on line 4—4, Fig. 1; Fig. 5 is a sectional view of a fragment of the casing taken at a point angularly removed from the section of Fig. 1; and Fig. 6 is a view illustrating how my invention may be used for a single stage machine.

Referring to the drawing, Figs. 1 to 5, wherein I have shown a two-stage compressor, 10 indicates a shaft having mounted thereon the impellers 11, each comprising the usual web member 12 with vanes 13 on opposite sides thereof, the vanes having curved entrance edges 13^a. The casing comprises an admission end section 14, a discharge end section 15, and an intermediate section 16. The admission end section 14 (Figs. 1 and 2 and 5) is made in two parts, being divided horizontally in an axial plane. It has an outer end wall 17 and an inner wall 18, the two being fixed in spaced relation to each other by the webs 19 and 20, Fig. 2, thus forming an admission chamber 21. 22 indicates a shaft packing arranged in an opening 23 at the center of the end wall. The webs 19, of which there are two, extend down close to the packing member 22, so as to prevent the air or other gas being pumped from circulating around the shaft on its way into the impeller. The end wall 17 has formed integral therewith a curved flange 24, and the inner wall 18 has a curved flange 25 spaced from the

flange 24 and joined to it by webs 26, Fig. 2. This forms a continuous circumferential passage 27, except that it is divided by the webs 26, which communicates with the admission chamber 21. 28 indicates the admission conduit of the compressor, it being formed as a part of the end section 14.

The discharge end section 15 comprises an outer end wall 29, an intermediate wall 30, and an inner wall 31. The intermediate wall 30 is spaced from the outer wall 29 to form a discharge chamber 32. It is connected to the outer wall 29 at the central portion as indicated at 33, and also by means of suitable webs 34. There is an opening 35 at the center to receive the shaft packing 36. Formed integral with the end wall 29 is a curved flange 37 and the intermediate wall 30 is provided with a flange 38 connected to the flange 37 by webs 39, Fig. 4. This forms a continuous circumferential passage 40, except that it is divided by the webs 39. Formed integral with the intermediate wall 30 and concentric with the flange 38 is a second flange 41 to which the circumferential edge of the inner wall 31 is fixed. The intermediate wall 30 and inner wall 31 are spaced apart by webs 42 and 43. The webs 42 extend down to the packing 36, while the webs 43 terminate short thereof. The specific arrangement of webs similar to these is well shown in Fig. 3, as will be explained hereinafter. The annular space between the flanges 38 and 41 is crossed by a series of partition walls 44 forming passages 45 which connect the space between the intermediate wall 30 and inner wall 31 with the annular passage 40. Between the walls 44 forming the passages 45 are left passages 46 extending to the discharge chamber 32. 47 indicates the discharge conduit which communicates with the discharge chamber 32. 48 indicates a bearing for the shaft 10. It is carried by a frame 49 fixed by bolts 50 to the end casing section 15.

The intermediate section, (Figs. 1, 3 and 5) comprises an annular wall 55 to which is fixed a diaphragm 56. The diaphragm 56 extends down to the shaft and forms the dividing wall between the two stages of the machine. The diaphragm 56 is provided on the one side with two concentric flanges 57 and 58. Between the outer flange 57 and the wall 55 is formed an annular passage 110

58* which forms a continuation of passage 27 in the admission end section 14. 59 is an annular wall fixed to the edge of flange 58 and spaced from it by webs 60 and 61. 5 As shown in Fig. 3, the two webs 60 extend down to the shaft for the reason already explained, while the webs 61 terminate short thereof. Extending across between the flanges 57 and 58 are suitable 10 walls 62 which form ducts 63 connecting the space between the diaphragm 56 and the wall 59 with the passage 58*. Between the walls 62 are left the passages 64 which connect with a chamber 65 on the other side of 15 the diaphragm which is formed by a wall 66 spaced from the diaphragm and joined to it by web members 67 arranged as are the other similar web members already described. The wall 66 has a flange 69 which 20 forms with the wall 55 an annular passage 70 which connects with the passage 40 in the discharge end casing 15. At the bottom of the machine are suitable openings 71 communicating with the various chambers and 25 through which foreign material entrapped therein may be withdrawn.

When the casing sections are assembled, as shown in Fig. 1, the walls 18 and 59, and 31 and 66 form between them chambers in 30 which the impellers 11 run, and between these walls around the periphery of the impellers are located the discharge vanes 72, which are carried by rings 73 located in 35 recesses in the respective walls. The discharge 40 vanes 72 and their relation to the impeller is best shown in Fig. 4.

In operation, the fluid, (as air or gas) being compressed or pumped, enters the chamber 21 through inlet conduit 28 and circulates entirely around the shaft. The lower web 19, located centrally in the inlet conduit divides the incoming fluid into two separate streams. From chamber 21 part of the fluid is fed to the right-hand side of 45 the impeller around its entire periphery. Another part of the fluid flows by way of passages 27, 58* and 63 into the chamber formed between walls 56 and 59, from which 50 chamber it is fed to the left-hand side of the impeller. This chamber extends entirely around the shaft so that this side of the impeller also receives fluid around its entire periphery. The fluid discharged from this impeller after passing through the discharge 55 vanes 72 flows through the passages 64 (see Fig. 3) into the chamber 65, from which it is fed to the right-hand side of the second stage impeller. Fluid also flows from the passages 64 through passages 70, 60 40 and 45 to the chamber between walls 30 and 31, from which it is fed to the left-hand side of the impeller, the impeller having complete peripheral admission on both sides, as in the case of the impeller of the first 65 stage. The fluid discharged from the sec-

ond stage impeller flows by way of passages 46 to the discharge chambers 32, from which it passes to discharge conduit 47.

By the above described arrangement, I provide an improved structure comprising 70 standard casing sections from which a machine having any number of stages from one up may be built. For a single stage machine, the two end sections 15 and 17 may be placed directly together. This is shown 75 in Fig. 6. When so arranged, as will be clear from an inspection of Fig. 1, the chamber for the impeller will be formed between the two walls 18 and 31, and circumferential passage 27 of the admission end section of 80 the casing will communicate directly with circumferential passage 40 of the discharge end section of the casing. For a two-stage machine, as shown in Fig. 1, the two end sections and one intermediate section is required; for a three-stage machine, the two end sections and two intermediate sections are required, and for machines of more stages it is simply necessary to add more intermediate sections. I am thus enabled to 85 use the same set of patterns for machines of any number of stages which greatly reduces the cost of manufacture. The structure also has the advantage that it can readily be made to accommodate impellers of different 90 width. If the impeller is to be narrower than standard, then abutting ends of the respective sections can be turned down by the necessary amount. On the other hand, if the impeller is to be made wider, then the 95 patterns can be built up by means of filling strips to add the necessary width to the casing parts, this being a comparatively simple and inexpensive matter.

In comparing an intermediate section 105 with the two end sections, it will be noted that (referring to Fig. 1) the walls and passages on the right-hand side of diaphragm 56 are substantially a duplicate of the walls and passages of the discharge end section, 110 and that those on the left-hand side are substantially a duplicate of those of the admission end section. It is due to this arrangement that a machine of any number of 115 stages may be built up from the three types of standard casing sections.

A further advantage of my improved structure is that with the casing sections built as shown, all machining can be done on a boring mill with one setting. Furthermore, there are no parts that require machining that have to be reached inside of the castings themselves.

It is also to be noted that in every instance the fluid to be pumped is fed radially 125 to each side of the impellers and entirely around the same, no circulating of fluid around the edges of the impellers being required in order to obtain the complete peripheral admission desired. This results 130

from the spaced radial arrangement of the various web members which form passages leading radially to the edges of the impeller, and the admission openings which 5 enter near the outer end of each radial passage. It has the advantage that the angle of the entrance ends of the impeller vanes can be designed to give much more efficient operation since they can be made to feed 10 the fluid to be pumped evenly to the impeller vanes.

In accordance with the provisions of the patent statutes, I have described the principle of operation of my invention, together 15 with the apparatus which I now consider to represent the best embodiment thereof; but I desire to have it understood that the apparatus shown is only illustrative, and that the invention can be carried out by other 20 means.

What I claim as new and desire to secure by Letters Patent of the United States, is—

1. A centrifugal compressor comprising complementary sections having walls which 25 form between them an impeller chamber, walls forming an annular chamber on each side of the impeller chamber from which fluid is fed to the opposite sides of the impeller through an angle of 360° , walls forming 30 two concentric annular passages which surround the chambers, ducts connecting the outer one with the annular chamber on one side of the impeller, the inner one forming a discharge chamber for the impeller, and an 35 inlet conduit and a discharge conduit connected with the compressor.

2. A centrifugal compressor comprising an admission end section, a discharge end section, and one or more intermediate sections, said sections having walls which form 40 impeller chambers between them, and other walls which form an annular chamber on each side of each impeller chamber and two surrounding concentric passages, spaced 45 ducts connecting the outer passage with an annular chamber on one side of an impeller chamber, the inner passage serving as a discharge chamber for the impeller, and inlet and discharge conduits connected with the 50 end sections.

3. A centrifugal compressor comprising an admission end section, a discharge end section, and one or more intermediate sections, each of said intermediate sections comprising 55 a diaphragm, walls on one side of the diaphragm which are a duplicate of a part of the admission end section, walls on the other side of the diaphragm which are

a duplicate of a part of the discharge end section, said walls forming two complete 60 annular admission chambers located side by side for adjacent impellers, and walls forming two concentric annular passages surrounding each impeller and appurtenant thereto, the inner one of said passages forming a discharge chamber for the impeller which it surrounds and being in communication with one of said annular admission chambers, and the outer one of said concentric annular passages being connected to the 70 other of said annular admission chambers.

4. A centrifugal compressor comprising an admission end section, a discharge end section, and one or more intermediate sections, said sections having walls which form 75 impeller chambers, one of such walls being a part of each end section and the remaining walls being part of the intermediate section or sections, said sections also comprising walls which form annular chambers on each 80 side of the impeller chambers, radial webs in the last named chambers for directing the fluid to be pumped to the entrance edges of the impellers, walls forming two concentric annular passages surrounding each impeller 85 chamber, and ducts connecting the outer passage to the annular chamber on one side of an impeller, the other annular passage acting as a discharge chamber for such impeller.

5. A centrifugal compressor comprising an admission end section, a discharge end section, and one or more intermediate sections, said sections having walls which form 90 impeller chambers, one of such walls being a part of each section and the remaining walls being part of the intermediate section or sections, said sections also comprising walls which form annular chambers on each 95 side of the impeller chambers, radial webs in the last named chambers for directing the fluid to be pumped to the entrance edges of the impellers, walls forming two concentric annular passages surrounding each impeller chamber, ducts connecting the outer passage to the annular chamber on one side of an impeller, the other annular passage acting as a discharge chamber for such impeller, a 100 shaft, and impellers on the shaft located in the impeller chambers, the plane of division 110 between the respective casing sections extending centrally through said impellers and at right angles to the shaft.

In witness whereof, I have hereunto set my hand this 12th day of May, 1916.

LOUIS C. LOEWENSTEIN.
